Patented May 10, 1904.

UNITED STATES PATENT OFFICE.

CHARLES B. HARWARD, OF SHEPARD, OHIO.

MAIL-BOX.

SPECIFICATION forming part of Letters Patent No. 759,437, dated May 10, 1904.

Application filed May 2, 1903. Serial No. 155,362. (No model.)

To all whom it may concern:

Be it known that I, CHARLES B. HARWARD, a citizen of the United States, residing at Shepard, in the county of Franklin and State 5 of Ohio, have invented a certain new and useful Improvement in Mail-Boxes, of which the following is a specification.

This invention relates to mail-boxes, and has for its object to provide an improved 10 mounting for the boxes of rural-delivery systems whereby said boxes are arranged to yield when struck by a vehicle, so as to avoid damage thereby, and also to return automatically to their original and normal positions 15 after being released from the vehicle.

With these and other objects in view the present invention consists in the combination and arrangement of parts, as will be herein-after more fully described, shown in the accompanying drawings, and particularly pointed out in the appended claims, it being understood that changes in the form, proportion, size, and minor details may be made within the scope of the claims without departing 25 from the spirit or sacrificing any of the advantages of the invention.

In the drawings, Figure 1 is a perspective view showing a mail-box supported in accordance with the present invention. Fig. 2 is a 30 top plan view thereof, the box-supporting arm being broken and shown by dotted lines in different positions. Fig. 3 is a longitudinal sectional view of the box. Fig. 4 is a cross-sectional view thereof.

Like characters of reference designate corresponding parts in each and every figure of the drawings.

In carrying out the present invention a suitable support is employed, preferably a 40 post 1, to which is connected a substantially horizontal arm 2, mounted to swing at opposite sides of its normal position. Moreover, it is designed to have the arm automatically return to its normal position after being displaced; and therefore it is connected to the 45 post by means of a suitable double-acting spring-hinge 3 to permit of the arm swinging in opposite directions, as indicated by dotted lines in Fig. 2 of the drawings.

The mail-box is supported or carried at the

outer end of the arm and consists of a body 4, preferably cylindrical in shape and rigidly supported at opposite ends between two up-standing bracket-arms 5, rising from the swinging arm 2. In the top of this rigid box 55 is an opening 6, through which mail-matter is designed to be inserted and removed, and this opening is normally closed by means of a rotatable cover 7 of cylindrical shape and embracing the rigid box. In the bottom of 60 the cover is an opening 8, which is designed to be brought into alignment with the opening in the top of the box for the insertion and removal of matter.

From the foregoing description it will be 65 understood that the arm 2 is adapted to stand at substantially right angles to the post, and should a vehicle accidentally strike the box or arm the latter will yield and swing horizontally with the movement of the vehicle until the latter has cleared the box, and then the arm will automatically resume its normal position under the influence of the spring-hinge. By having a double-acting hinge the arm is 70 adapted to yield in either direction, and thereby obviate damage to the mail-box should a vehicle strike it.

While of course any type of box could be mounted upon the swinging arm, it is preferred to employ the type of box shown in the drawings and set forth in the foregoing description, as with this type of box it is not likely that the lid or cover will fly open during the swinging movements of the supporting-arm.

Having thus described the invention, what is claimed, and desired to be secured by Letters Patent, is

1. The combination with a support, of an arm hinged thereto to swing substantially 90 horizontally in opposite directions, a spring to automatically return the arm to its normal position after having been displaced therefrom, and a mail-box carried by the arm.

2. The combination with a post, of a horizontally-swinging arm connected to the post by means of a double-acting spring-hinge, and a mail-box carried by the arm.

3. The combination with a support, of a horizontally-swinging arm, a double-acting 100

spring-hinge connecting the arm to the support, opposite bracket members rising from the arm, a substantially cylindrical box rigidly supported by and between the bracket members and provided in its top with an opening, a rotatable substantially cylindrical cover embracing the box and journaled between and upon the bracket members and provided in its bottom with an opening for alignment with the opening in the top of the box.

4. A support for rural-delivery mail-boxes, embodying a substantially horizontal arm having a spring-actuated double-acting hinge at one end, a pair of box-supporting brackets rising from the opposite end portion of the

arm, a box supported between the brackets, and a rotatable cover mounted upon said brackets.

5. A rural-delivery mail-receiving device, comprising a support, an arm having one end hinged to the support to swing freely in a substantially horizontal plane in opposite directions from a normal position, a mail-box carried by the arm, and means for automatically returning the arm to its normal position after being displaced therefrom.

CHARLES B. HARWARD.
